UNITED STATES PATENT OFFICE

164,599

PAPER

Elizabeth Phelps, Holyoke, Mass., assignor to The Marvellum Company, Holyoke, Mass., a corporation of Massachusetts

Application May 16, 1951, Serial No. 15,192

Term of patent 7 years

(Cl. D59—2)

To all whom it may concern:

Be it known that I, Elizabeth Phelps, a citizen of the United States, residing at Holyoke, in the county of Hampden and Commonwealth of Massachusetts, have invented a new, original, and ornamental Design for Paper, of which the following is a specification, reference being had to the accompanying drawings forming part hereof.

The figure is a plan view of a piece of paper showing my new design.

I claim:

The ornamental design for a paper as shown.
ELIZABETH PHELPS.
